CARBURETOR

Alfred J. Farineau, Pittsburgh, Pa., assignor of
one-fifth to Richard M. Kuhn and one-fifth to
Ralph C. Corey, both of Pittsburgh, Pa.

Application October 27, 1937, Serial No. 171,256

7 Claims. (Cl. 123—121)

My invention relates to carburetors such as are employed for supplying a mixture of vaporized fuel and air to internal combustion engines.

One object of my invention is to provide a device for more effectively vaporizing gasoline or other liquid fuel, than is possible with various types of carburetors heretofore employed, to thereby effect economy in consumption of fuel, and to secure greater uniformity of operation of an internal combustion engine to which the fuel is supplied.

Another object of my invention is to provide means for supplying vaporized fuel to the intake line of an internal combustion engine, at predetermined pressures.

Still another object of my invention is to provide means for effectively maintaining a constant ratio of fuel and air to the supply line or intake manifold of an internal combustion engine.

20 The single figure of the drawing is a side view, partially in section, of apparatus embodying my invention.

In the drawing, the numeral 2 indicates a fuel intake line leading to the cylinder or manifold of an internal combustion engine (not shown). Air for the explosive mixture is supplied through an intake 3 to which an air cleaner may be applied, as indicated at 4. A fuel supply chamber 5 is provided for starting and initially running the engine. The fuel level in the chamber 5 is controlled by a float-operated valve 6. Upon starting of the engine, fuel is drawn from the chamber 5 through a jet or spray nozzle 7 and the suction created in the line 2 will also draw air from the intake 3, past a valve 8. Flow of gasoline to the jet pipe 7 is controlled by a valve 9 that is normally held in raised position by a spring 10. Upon development of vaporized fuel pressure within the system, as hereinafter explained, the valve 9 is automatically closed by such vapor pressure acting through a port 11. When the pressure within the port 11 reaches a predetermined degree, the valve 9 will be forced down against the pressure spring 10 to close a port 12 through which communication is afforded between the chamber 5 and the jet pipe 7. Fuel supply to the motor is controlled by the usual throttle valve 13, operated in a suitable or ordinary manner.

50 My invention contemplates that during normal running of the engine, the explosive mixture therefor, shall consist of vaporized gasoline or other motive fluid supplied under pressure, and mixed with a suitable quantity of air. In order 55 to effect vaporization and compression of the

liquid fuel, the engine is initially started and run for a short period of time through the medium of fuel supplied from the chamber 5. Upon starting of the engine, the vaporization and compression of the main supply of motive fuel is begun. To this end, I provide a double-acting pump which includes a chamber or casing 15 containing a pump diaphragm 16, which divides the chamber 15 into compartments 17 and 17a. The diaphragm 16 is reciprocated by a rod 18, that is in turn actuated from any suitable moving part of the engine, such as the crank shaft, water or oil pump shafts, etc. The pump serves to circulate air through a body of gasoline contained within a reservoir 19, and to place the vapor-laden air under pressure.

Gasoline or other motive fluid is supplied from a line 20, which may also supply the chamber 5. The gasoline is under pressure, and will enter the reservoir 19 past a valve 21 that is controlled by a float 22, which will maintain a predetermined level within the reservoir. A bubble compartment 23 is provided in the reservoir and air is circulated upwardly through this compartment to effect vaporization of the fuel.

In circulating the air, movement of the pump diaphragm 16 toward the left will draw air into the compartment 17 of the pump chamber, past an inwardly-opening check valve 24, and will force vapor out of the compartment 17a at the opposite side of the diaphragm. Movement of the diaphragm in the opposite direction will force air out of said compartment 17, past a check valve 25, from whence it enters a pipe 26 leading to a nozzle 27 in the lower portion of the bubble compartment 23, the air being discharged through the upper perforated portion of the nozzle 27. A perforated baffle plate 28 is provided above the liquid level in the bubble compartment, against which upwardly-moving drops of fuel will impinge. The air passes from the compartment 23 to a pipe 29 and thence to a pipe 30 where it again is drawn past the valve 4. Continued circulation of the air in this manner results in effective vaporization of the gasoline. Additional air is automatically drawn in past a check valve 31, in accordance with the demands on the system, the valve 31 opening to admit additional air as required when the valve 24 is opened upon suction stroke of the pump diaphragm 16.

The pump also serves to withdraw vapor from the circulating system just described, and to move it to a vapor reservoir. To this end, I provide a check valve 32 located above the liquid level in the bubble chamber 22. Upon movement of

the diaphragm 16 to the right, vapor will be drawn from the bubble compartment, past this valve 32 into the compartment 17a of the pump chamber. Upon movement of the diaphragm to the left, the body of vapor thus withdrawn will be forced past a check valve 33 into a line 34 which leads to a vapor reservoir 35.

The area of the port opening of the valves 24 and 25 is materially greater than the area of port opening of the valve 32, so that there will be always a body of vapor moving through the circulating system, a portion of which is drawn past the valve 32 and discharged into the reservoir 35. Sufficient air is admitted through the valve 31 to replace the vapor thus withdrawn from the circulating system.

In order that the pressure within the reservoir 35 will not exceed a predetermined degree, I provide a relief valve 36 connected through a pipe 37 with the vapor reservoir 35 and through a pipe 38 with the circulating system. In this case, the vapor thus returned to the circulating system will cause a corresponding reduction in the amount of air admitted through the valve 31.

25 The reservoir 35 is jacketed to provide a space 39 through which hot water from the engine-cooling system or exhaust gases may be circulated in order to heat the vapor and prevent condensation thereof. Inlet and outlet openings 40 and 41 are provided for circulating the heating medium.

When the body of vapor within the reservoir 35 becomes built up to a predetermined pressure, it will move a valve 42 from its seat and flow through a branched line or conduit 43 to an outlet 44 located within a metering chamber 45, interposed between the air inlet 3 and the passageway 2. The outlet 44 discharges into a sleeve 46 that has valve openings 47 of generally triangular form. Discharge through the openings 47 is controlled by a sleeve member 48 which has telescopic movement with respect to the member 46 and is provided with discharge ports 49 in its sides. When the ports 49 are brought into registry with the ports 47, vapor will flow from reservoir 35 into the metering chamber 45. It will be seen that as the vapor under pressure enters the pipe 43, a portion thereof will flow through the port 41 and cut off flow of gasoline from the chamber 5 to the spray head 7, thereby automatically transferring the source of supply of combustible fuel from the chamber 5 to the reservoir 35, or in other words, from the liquid source to the vapor source.

55 It will be understood that under idling conditions of the engine, with the throttle valve 13 in nearly closed position, the intake suction will be of a low degree and the valve 8 drawn only a short distance from its seat, against the pressure of a spring 8a. The valve 8 has its stem connected to the valve member 48, so that as the valve 8 moves down, the ports 49 of the valve member 48 will be brought into registry with the ports 47, whereupon fuel vapor will flow into the air stream and be carried to the engine manifold. There need, of course, be only a small supply of fuel vapor during idling, and since the upper ends of the ports 45 are of narrow width, they 60 will be uncovered to only a small extent at idling stage. At greater throttle openings, as under driving conditions, the valve 8 will be drawn farther from its seat, and as the valve member 48 is thereby moved downwardly, the area of port 65 opening as between the triangularly shaped ports

47 and the ports 49 will be correspondingly increased.

It will be understood that the setting of the valve 42 is such that it will open at lower reservoir pressure than will the valve 36. The pump is of sufficient capacity to maintain a desired pressure within the reservoir 35 at maximum demands of the engine, so that there will always be proper proportioning of the vapor and air which forms the combustible mixture.

10 While vaporization could be effected to some degree by passing a stream of air only once through a body of gasoline, such procedure results in vaporizing only the lighter constituents of the gasoline. I have found that by repeatedly 15 passing a given body of air through the gasoline, it is possible to effect more complete vaporization and to secure a more richly laden vapor.

I claim as my invention:

1. Apparatus for forming explosive charges for 20 internal combustion engines and the like, comprising means for circulating air through a body of liquid fuel, means for withdrawing the mixture thus produced and placing it under pressure, means automatically operable when said pressure 25 attains a predetermined degree for directing the compressed mixture into an air stream, and means for varying the volume of mixture supplied to the air stream in accordance with changes in air flow.

30 2. Apparatus for forming explosive charges for internal combustion engines and the like, comprising means for creating flow of air through a body of liquid fuel, a pump for compressing the mixture thus produced, a reservoir for receiving 35 the compressed mixture, an air conduit, means actuated by pressure in the reservoir for controlling flow from the reservoir to said conduit, a valve for controlling the flow of air in said conduit, and means controlled by movement of said 40 valve for varying the rate at which the compressed mixture flows from the reservoir into the air stream.

3. Apparatus for forming explosive charges for 45 internal combustion engines and the like, comprising a fuel intake line for an engine, means operative through suction in said line for effecting discharge of a jet of liquid fuel into the line, means for effecting flow of air through a body of liquid fuel, means for compressing the mixture 50 thus produced, means for directing the compressed mixture into said intake line, and means actuated by the mixture when compressed to a predetermined degree, for shutting off the first-named supply of fuel to the said line.

55 4. Apparatus for forming explosive charges for internal combustion engines, comprising a fuel intake line for an engine, means for effecting discharge of liquid fuel into said line, means for producing a vaporized mixture of air and liquid 60 fuel, means for compressing said mixture and forcing it into said line, and means actuated by the compressed mixture, for shutting off the said discharge of liquid fuel.

65 5. Apparatus for forming explosive charges for internal combustion engines and the like, comprising a pump operable in predetermined relation to engine speed, for circulating air through a body of liquid fuel and placing under pressure 70 the mixture of fuel and air thus produced, means for directing the said compressed mixture into an air stream to form an explosive mixture, an air intake for the pump, and means automatically operable when the pressure of said fuel mixture exceeds a predetermined degree, for directing a 75

portion of said mixture to the pump, to thereby reduce the amount of air admitted to the pump and control the pressure of said mixture of fuel and air.

- 5 6. Apparatus for forming explosive charges for internal combustion engines and the like, comprising a pump operable in predetermined relation to engine speed, for circulating air through a body of liquid fuel and placing under pressure the mixture of fuel and air thus produced, means for directing the said compressed mixture into an air stream to form an explosive mixture, an air intake for the pump, means automatically operable when the pressure of said fuel mixture exceed a predetermined degree, for directing a portion of said fuel mixture to the pump, to thereby reduce the amount of air admitted to the pump and control the pressure of said mixture
- 10
- 15

of fuel and air, and means automatically operable when the said pressure falls below a predetermined point, for shutting off flow of the fuel mixture to the air stream.

7. Apparatus for forming explosive charges for internal combustion engines and the like, comprising means for circulating air through a body of liquid fuel, means for withdrawing the mixture thus produced and placing it under pressure, means for directing the compressed mixture into an air stream, means for varying the volume of mixture supplied to the air stream, in accordance with changes in air flow, and means automatically operable by said pressure, independently of said varying means, for controlling the flow of the mixture into the air stream.
